UNITED STATES PATENT OFFICE

2,505,127

GARMENT HANGER

Walter Ludwig, Detroit, Mich., assignor to L. A. Young Spring and Wire Corporation, Detroit, Mich., a corporation of Michigan

Application August 24, 1946, Serial No. 692,765

6 Claims. (Cl. 223—92)

1

This invention relates to improvement in garment hangers.

The main objects of the invention are:

First, to provide an efficient garment hanger comprising a suspending hook of wire and a supporting yoke of tubular cross section and of fibrous material in which both the hook and supporting yoke are conformed and shaped to facilitate ready assembly of the hook in supporting relation to the yoke.

Second, to provide a garment hanger comprising a suspending member of wire and a supporting member of tubular cross section and of fibrous material in which both the suspending member and tubular supporting member are conformed and shaped to facilitate ready assembly of the suspending member in suspended relation to the bottom wall of the tubular supporting member.

Third, to provide a garment hanger having these advantages which is attractive in appearance and economical to produce.

Objects relating to details and economies of the invention will appear from the description to follow. Structures illustrating preferred embodiments of the invention are shown in the accompanying drawing, in which:

Fig. 1 is a side elevation of the hanger embodying the features of the invention.

Fig. 2 is a fragmentary longitudinal vertical section of the outer end of one of the yoke arms illustrating one embodiment of a wire suspending member in assembled relation to the yoke arm.

Fig. 3 is a fragmentary bottom plan view of the outer end of one of the yoke arms with the wire suspending member of Fig. 2 omitted.

Fig. 4 is a fragmentary view partially in longitudinal vertical section of the outer end of one of the yoke arms illustrating another embodiment of a wire suspending member in assembled relation to the yoke arm.

Fig. 5 is a side elevation illustrating the embodiment of Fig. 4 prior to assembly to the yoke arm.

Fig. 6 is a transverse vertical section through one of the yoke arms illustrating another embodiment of a suspending member in assembled relation to the yoke arm, and

Fig. 7 is a fragmentary view in central longitudinal vertical section of the yoke member at the apex thereof illustrating the suspending hook in assembled relation to the yoke.

Referring to the drawing, the garment hanger comprises a yoke 1 having downwardly diverging garment supporting arms 2, this yoke in the

2

preferred embodiment of the invention being integrally formed of a paper tube. The apex 3 of the yoke has the under wall 4 collapsed upwardly longitudinally centrally thereof against the upper wall 5 providing a downwardly opening groove-like recess 6 in the bottom wall extending longitudinally of the yoke. The outer ends of the yoke arms are conformed and shaped to provide longitudinally downwardly curved garment supporting portions 7, and to provide upwardly collapsed lower walls having downwardly opening groove-like recesses 8 extending longitudinally of the yoke arms. The collapsed portions and groove-like recesses at the apex and outer ends of the yoke member give rigidity thereto and facilitate bending the same to shape.

The tube is formed of a plurality of layers or plies of paper, as conventionally shown in Figs. 2, 4, 6 and 7, which are convolutely or otherwise wound into tubular formation and cemented together. The tube in its entirety may be collapsed and conformed to the shape, as shown and above described, in the process of manufacture of the same quite promptly after the tube is formed and before the glue or cement used in cementing the plies together has set.

The suspending hook designated generally as 9 is preferably formed of a piece of wire of suitable gauge folded upon itself to provide a hook portion 9, the bight of the fold constituting the bill 10 of the hook as shown in Fig. 1. The strands are twisted together to form at least a portion of the shank 11, the lower ends of strands of the shank below the twist thereof terminating in laterally offset downwardly diverging arms 12 terminating in depending vertical portions 13, outwardly bent at their lower ends to form downwardly diverging arms 14 having at their ends upwardly projecting prongs 15. The depending vertical portions 13 springably engage the outer ends of a pair of substantially spaced aligned slots 16 extending through and longitudinally of the upper wall 5 of the yoke at the apex 3 thereof. The arms 14 are disposed within and project longitudinally of the yoke arms 2, with the prongs 15 at the outer ends thereof supportingly engaging the bottom of the upper wall of the yoke arms. The substantial spacing and length of the strands beneath the twisted shank 11 permit the same to be readily forced or pressed towards each other into the dotted line position shown in Fig. 7 whereby the arms 14 with their prongs 15 may be inserted through the slots 16 to the interior of the yoke arms as shown in full lines in Fig. 7. This assembly of the suspending

hook to the yoke member may be readily performed with or without the use of tools. The previously described construction for connecting the suspending hook to the yoke constitutes the subject matter of divisional application Serial No. 760,382, filed July 11, 1947.

To permit a garment to be dependingly supported from beneath the arms 2 of the yoke member I provide suspending members 18 connected to the bottom wall of the yoke arms. These suspending members are provided with depending loops adapted to receive safety pins 181 or other garment supporting means as shown in Fig. 1. In the embodiment of the invention of Fig. 2 the suspending member 18 is made of wire conformed to U-shape and provided with upwardly extending outwardly inclined arms 19 connected at their lower ends by the depending loop portion 20, and terminating at their upper ends in outwardly bent downwardly inclined prong-like portions 21. The arms 19 springably engage the ends of a slot 22 extending through and longitudinally of the bottom wall of the yoke arm, and the lower ends of the prongs 21 are supportingly engaged within the yoke arm on the bottom wall thereof. The elasticity of the suspending member permits the arms 19 to be pressed towards each other whereby the prongs 21 may be inserted through the slot 22 and into the operative supported position in the yoke arm as shown in Fig. 2. This construction provides a very secure connection between the suspending loop and the yoke and permits a ready assembly of the parts.

In the embodiment of the invention of Fig. 4 the suspending member 23 comprises a wire conformed to provide a depending lower loop portion 24 and upwardly projecting inwardly inclined arms 25 crossing each other adjacent their upper ends and terminating in outwardly inclined downwardly projecting yoke engaging prongs 26. The arms 25 extend through the yoke slot 22 and the prongs 26 are engagingly supported by the bottom wall of the yoke arm longitudinally beyond the ends of the slot 22. The suspending member 23 prior to assembly to the yoke is conformed to the shape shown in Fig. 5. After the prongs 26 are inserted through the slot 22 the arms 25 are pressed towards each other into the assembled position shown in Fig. 4. Due to the relative softness and inelasticity of the wire the suspending member permanently retains the shape of Fig. 4. This embodiment is otherwise similar to that of Fig. 2.

In the embodiment of Fig. 6 the suspending member 27 is provided with downwardly projecting prong-like portions 28 supportingly engaged by the lower wall 4 of the yoke arms. These prong-like portions are disposed in planes extending transversely of the slot 22 so as to engage the wall of the yoke on the opposite sides of the slot 22. The construction is otherwise similar to that of any of the other embodiments.

The foregoing structures are characterized by the inexpensiveness of the production thereof, by their rigidity, resistance to displacement and effectiveness in supporting garments. The operation of assembling the same may be readily performed and once assembled the hanger is capable of repeated use without likelihood of coming apart or becoming unstable.

Embodiments of the invention which incorporate the principles thereof in a highly desirable manner have been illustrated and described. It should be understood that the foregoing terminology is used descriptively rather than in any

limiting sense and with full intent to use equivalents of the features shown and described within the scope of the following claims.

Having thus described my invention, what I claim as new and desire to secure by Letters Patent, is:

1. A garment hanger comprising a supporting yoke of tubular cross section and of fibrous material and having downwardly diverging garment supporting arms, a suspending hook connected to the yoke at the apex thereof, the under wall of each yoke arm having a slot elongated in the direction of the length of the arm, and a suspending member comprising a loop-like lower portion and spaced upwardly extending arms, said arms terminating at their upper ends in outwardly bent downwardly projecting prongs, the arms being disposed through said slot and springably engaging the under wall of the yoke arm at the ends of the slot, said prongs being disposed within the yoke arm and supportingly engaged by the under wall of the yoke longitudinally beyond the ends of the slot, said loop-like portion depending beneath the yoke arm to receive means for supporting a garment from beneath the yoke.

2. A garment hanger comprising a supporting yoke of tubular cross section and of fibrous material and having downwardly diverging garment supporting arms, a suspending hook connected to the yoke at the apex thereof, the under wall of each yoke arm having a slot elongated in the direction of the length of the arm, and a suspending member comprising a loop-like lower portion and spaced upwardly extending arms, said arms terminating at their upper ends in outwardly bent downwardly projecting prongs, the arms being disposed through said slot, said prongs being disposed within the yoke arm and supportingly engaged by the under wall of the yoke longitudinally beyond the ends of the slot, said loop-like portion depending beneath the yoke arm to receive means for supporting a garment from beneath the yoke.

3. A garment hanger comprising a supporting yoke of tubular cross section and having downwardly diverging garment supporting arms, a suspending hook connected to the yoke at the apex thereof, the under wall of each yoke arm having a slot elongated in the direction of the length of the arm, and a suspending member comprising a loop-like lower portion and spaced upwardly extending arms, said arms terminating at their upper ends in outwardly bent downwardly projecting prongs, the arms being disposed through said slot, said prongs being disposed within the yoke arm and supportingly engaged by the under wall of the yoke, said loop-like portion depending beneath the yoke arm to receive means for supporting a garment from beneath the yoke.

4. A garment hanger comprising a garment supporting member of tubular cross section and of fibrous material, a suspending hook for supporting said garment supporting member, and a suspending member for supporting a garment from beneath said supporting member, the bottom wall of said garment supporting member having an opening therethrough, said suspending member having a lower loop-like portion and upwardly extending arms disposed in crossed relation to each other and terminating in laterally projecting portions, said lower loop-like portion depending below the supporting member, said upwardly extending arms projecting

through said opening, and said laterally projecting portions being disposed within said supporting member and supportingly engaged by the lower wall thereof.

5. A garment hanger comprising a garment supporting member of tubular cross section and of fibrous material, a suspending hook for supporting said garment supporting member and a suspending member for supporting a garment from beneath the supporting member, the bottom of said supporting member having an opening therethrough, said suspending member having a U-shaped lower portion and upwardly extending arms terminating in outwardly projecting prong-like members, the U-shaped lower portion depending beneath the supporting member, the upwardly extending arms projecting through said opening, and the outwardly projecting prong-like portions being disposed within the supporting member and supportingly engaged by the lower wall thereof.

6. A garment hanger comprising a supporting member of tubular cross section, a suspending hook for supporting said garment supporting member, a suspending member for supporting a garment from beneath the garment supporting
